UNITED STATES PATENT OFFICE.

JOHN F. HERMAN, OF BRIDGEPORT, CONNECTICUT.

REAMER.

1,107,304.

Specification of Letters Patent. Patented Aug. 18, 1914.

Application filed September 17, 1913. Serial No. 730,233.

To all whom it may concern:

Be it known that I, JOHN F. HERMAN, a citizen of the United States, residing at Bridgeport, in the county of Fairfield and State of Connecticut, have invented certain new and useful Improvements in Reamers; and I do hereby declare the following to be a full, clear, and exact description of the invention, such as will enable others skilled in the art to which it appertains to make and use the same.

This invention comprehends improvements in reamers and relates more particularly to those of the type which are provided with a plurality of cutters adapted for simultaneous adjustment.

One of the objects of the invention is to provide a reamer of this type which shall be of extremely simple construction, cheap to manufacture, and very strong and durable.

Another and more specific object of the invention resides in the provision of a reamer including a longitudinally slotted shell or body, a cutter adjustably mounted within each of said slots and novel means for adjusting the cutters and locking them to the shell or body which forms the holder.

The invention also aims to generally improve devices of this nature to render them more useful, practical and commercially desirable.

With these and other objects in view, as will become more apparent as the description proceeds, the invention consists in certain novel features of construction, combination and arrangement of parts as will be hereinafter fully described and claimed.

For a complete understanding of my invention, reference is to be had to the following description and accompanying drawings, in which—

Figure 1 is a side elevation of my improved reamer, Fig. 2 is a longitudinal sectional view with the cutter shown in elevation, Fig. 3 is a side elevation of the shank and cutter holder which is formed thereon, Fig. 4 is an end elevation of Fig. 3, Fig. 5 is a section taken on the plane of line 5—5 of Fig. 3, Fig. 6 is a central sectional view through one of the barrels, Fig. 7 is an end elevation of one of the barrels, Fig. 8 is an end elevation of the reamer, Fig. 9 is a transverse fragmentary sectional view through the cutter holder, Fig. 10 is a section on the plane of line 10—10 of Fig. 2,

and Fig. 11 is a section taken on the plane of line 11—11 of Fig. 3.

Referring in detail to the drawings by numerals, 1 designates, generally, the shank which is formed with an externally threaded portion 2 near one end of which is also provided an enlarged frusto-conical head 3 upon the outer end thereof. A cylindrical shell or body 4 which forms the holder for the cutters, to be described later, is formed integrally with the head 3 and is open at its outer end. This shell is formed with longitudinal slots 5 which extend the full length thereof and which divide said shell into a number of sections 6. The forward face of each of the slots 5 is disposed in one of the radial planes of the barrel 4, as will be apparent upon reference to Figs. 4 and 8. The head 3 is formed with a plurality of slots 7 which are of somewhat less width than the slots 5 and which are alined therewith.

A spindle 8 provided with oppositely threaded portions 9 and 10 respectively, is fitted at one end within an axial opening 11 which extends through the head 3 into the shank 1. The spindle is rotatably secured within the opening 11 by means of a key 12 which has a threaded head 13 adapted to fit within the opening 14 formed in the shank 1. The key extends at right angles to the spindle and projects within an annular channel 15 formed therein, whereby the spindle is allowed a rotational movement, but prevented from moving longitudinally relative to the shank. If desired, the key may be made with a slight taper so that, as it wears, it may be threaded farther inwardly so as to maintain a close engagement with the walls of the channel 15.

A pair of barrels 16 and 17 are mounted upon the spindle 8 within the shell 4 and are threaded upon the portions 9 and 10 of said spindle. These barrels are cylindrical in form and are provided with a plurality of inclined grooves or recesses 18, the recesses of one barrel being inclined in a direction opposite to the recesses of the other barrel. These recesses 18 correspond with the slots 5 formed in the shell 4 and are adapted to receive the cutters 19.

The inner edge of each cutter is parallel with the outer edge for a portion of its length, as indicated by the numeral 20, and is inclined adjacent its ends, as indicated by the numeral 21. The inclined portions 21

ride upon the inclined bottom walls of the grooves or recesses 18. The inner end of each of the cutters has formed thereon a longitudinally extending arm 22 which extends 5 parallel with the slots 7 formed in the head 3. The slots 7 and the arms 22 are inclined at the same angles to the center of the shank 1.

A stop ring 23 is mounted for longitudinal movement upon the portion 2 of the shank 1, and has its bore enlarged at its outer end to form a channel 24. This channel is of a frusto-conical shape and the wall thereof is parallel with the outer faces of 15 the arms 22, said arms being adapted to project a distance within the chamber, as shown in Fig. 2. The ring is held against rotational movement by means of the pin 25 which works within a longitudinal groove 20 26 formed in the periphery of the portion 2 of the shank. A sleeve or nut 27 is threaded upon the portion 2 of the shank for engagement with the ring 23, and is provided upon its periphery with knurling, as indicated by 25 the numeral 28, and with graduations, indicated by the numeral 29. The ring 23 carries a zero mark 30 which cooperates with the graduations on the nut so as to indicate the distance which the nut is rotated. The 30 graduations 29 are spaced with regard to the pitch of the threads upon the nut, and therefore the longitudinal movement of the nut can be easily ascertained. The cutters are fastened securely to the shell or holder 35 4, by means of screws 31.

When it is desired to adjust the cutters outwardly, the screws 31 are loosened and the nut, or sleeve 27 threaded inwardly. Then the spindle 8 is rotated by means of a 40 screwdriver inserted in the slot 32 in such a direction as to cause the barrels 16 and 17 to move toward each other. This movement of the barrels will cause the inclined walls of the recesses 18 to force the cutters outwardly. The limit of this outward movement is checked by the stop ring 23 which 45 overlaps the arms 22, as previously mentioned. When the proper adjustment has been made, the screws 31 are tightened and 50 the reamer is ready for use. The distance which the cutters move outwardly is determined by the amount of rotation given to the nut 27 since this nut controls the position of the stop ring 23, and the latter in 55 turn controls the movement outward of the arms 22.

From the foregoing description taken in connection with the accompanying drawings, it will be apparent that I have pro-

vided a very simple and practical reamer in 60 which the cutters may be simultaneously adjusted with a great degree of accuracy. It will be understood that the cutters may be provided with different forms of cutting edges and that they may be threaded, if it is 65 desired, so that they may be used for tapping holes.

While I have shown and described the preferred embodiment of my invention, it will be understood that minor changes in 70 construction, combination and arrangement of parts may be made without departing from the scope and spirit of the invention as claimed.

Having thus described my invention, I 75 claim:—

1. In a reamer of the character described the combination with a shank, of a hollow cylindrical body formed on one end thereof, the body being provided with longitudinal 80 slots, a threaded spindle journaled in the outer end of the shank and extending axially through the body, a pair of barrels mounted upon the spindle in threaded engagement therewith, said barrels being formed with 85 oppositely inclined recesses, a plurality of cutters working through the slots formed in the body and seating within the recesses formed in the barrels; and means for limiting the outward movement of the cutters in 90 response to the pressure exerted by the barrels.

2. In a reamer the combination of a shank having a frusto-conical head formed on one 95 end thereof, a hollow shell formed upon the outer end of the head, said shell and head being formed with slots, a spindle journaled in the outer end of the shank and extending axially through the shell, a pair of barrels 100 carried upon the spindle in threaded engagement therewith, said barrels being formed with oppositely inclined recesses, a plurality of cutters extending through the slots in the shell and seating within the recesses, the inner edges of the cutters being 105 inclined to conform to the inclination of the recesses, arms formed upon the inner ends of the cutters for reception within the slots formed in the head; and a stop ring mounted upon the shank and formed with a chamber into which said arms project.

In testimony whereof I affix my signature in presence of two witnesses.

JOHN F. HERMAN.
